DESIGN FOR A SLIPPER OR SIMILAR ARTICLE

Hans Springer, New York, N. Y.

Application December 16, 1937, Serial No. 73,658

Term of patent 7 years

To all whom it may concern:

Be it known that I, Hans Springer, a citizen of Austria, residing at Hotel Shelton, New York, in the county of New York and State of New York, have invented a new, original, and ornamental Design for a Slipper or Similar Article, of which the following is a specification, reference being had to the accompanying drawing, forming part thereof.

In the drawing—

Fig. 1 is a side perspective view of a slipper or similar article, showing my new design;

Fig. 2 is a rear view, showing the enlarged heel inserted between the inner sole and the outer sole and tapering gradually down to the beginning of the shank of the shoe, the salient feature being the enlarged heel mentioned.

I claim:—

The ornamental design for a slipper or similar article as shown and described.

HANS SPRINGER.
